UNITED STATES PATENT OFFICE.

CHARLES G. SOUTHMAYD, OF CHICAGO, ILLINOIS.

FOUNTAIN-PEN.

SPECIFICATION forming part of Letters Patent No. 710,724, dated October 7, 1902.

Application filed April 24, 1902. Serial No. 104,610. (No model.)

To all whom it may concern:

Be it known that I, CHARLES G. SOUTHMAYD, a citizen of the United States, residing at Chicago, in the county of Cook and State of Illinois, have invented a new and useful Improvement 5 in Fountain-Pens, of which the following is a specification.

My invention relates to improvements in the class of fountain-pens in which the holder 10 containing the reservoir is adapted to be supplied with ink by a syringe or vacuum-producing action.

The more important objects of my invention are to generally simplify and otherwise 15 improve fountain-pens of the class referred to, to increase the capacity of the reservoir without lengthening the holder in filling the reservoir beyond the length of the holder in its most compact condition, to render the 20 holder proof against leaking, and to enable the reservoir-containing barrel and pen-stock to be formed in one continuous or jointless piece.

Referring to the accompanying drawings, 25 Figure 1 is a longitudinal sectional view of a fountain-pen provided with my improvements and shown in its condition ready for use. Fig. 2 is a similar view of the same without the pen-covering cap and with the parts in the 30 relative positions to which they are brought in evacuating the reservoir of any remnant of ink preparatory to refilling it; and Fig. 3 is a similar view of the same with all the parts except the cap in the relative positions 35 they occupy when the device is in condition for writing, with the reservoir supplied with its ink contents by bringing the parts into such relative positions.

As shown in the drawings, all the parts are 40 greatly exaggerated, for the sake of clearness, as to their normal dimensions.

A is the tubular barrel, formed preferably, as usual, of hard rubber, though my invention is not limited in the matter of material 45 employed for the parts, but is intended to include the employment of any suitable material. The barrel forms the ink-reservoir B and has upon it, near its forward end, a circumferential enlargement A', affording the 50 shoulders a and a' at its opposite ends. Beyond the shoulder a' the tubular barrel is extended as the nozzle a², shown as externally

tapered toward its forward extremity and with an internal circumferential shoulder a³ near its inner end, beyond which the nozzle 55 is provided with an internal circumferential shoulder a⁴. The part referred to as the "nozzle" corresponds with the pen-stock of other fountain-pens, which is formed in them separably from the barrel, but which my construction enables me to form in one piece with the barrel, including the enlargement A'.

C is the tubular quill fitting in the nozzle, wherein it abuts at its inner end against the shoulder a³ and forms therein, with the inner 65 wall surface of the nozzle, a cylindrical space b, into which to insert a pen D, which abuts at its inner end against the shoulder a⁴. The quill projects, as usual, beyond the nozzle a², and should register, as shown, at the mouth 70 c in its forward extremity, with the opening d in the split pen near its point.

The barrel A carries at its rear end a valve E, shown in its preferred form of an internally-threaded socket f, containing a vent-opening f' and formed in reduced external diameter on the end of a solid plug f², which preferably terminates in a projection f³. The socket f screws upon the threaded end e of the barrel A and presents thereon, at its forward end, a shoulder f⁴. By turning the socket in the direction to withdraw it the vent-opening clears the end of the barrel A, while turning it in the opposite direction screws the socket upon the barrel, and thereby closes 85 the vent f', which renders the socket a valve for the purpose hereinafter described and also brings the end of the barrel against the base of the socket, thereby effectually sealing the reservoir at its rear end. Packing v is 90 shown on the base of the socket, though it is not an indispensable necessary adjunct.

F is a tubular sleeve, preferably formed of hard rubber, like the barrel which it incloses telescopically, forming therewith the internal 95 circumferential air-space g, which is closed at its forward end by an internal enlargement h of the sleeve, presenting a shoulder h' and at which the sleeve closely hugs the outer surface of the barrel. The larger section of the plug f² also closely fits the interior of the sleeve F near its rear end, so that the space 100 g is thus practically air-tight.

G is the cap (also preferably of hard rub-

ber) to fit over the nozzle a^2 and abut against the shoulder a' , thereby shielding the pen D when out of use, the cap being vented, as shown at i , to prevent in its removal any suction action by it that would tend to pull ink out of the reservoir through the quill and pen. When the fountain-pen is being used, the cap G may be applied to the projection f^3 , on which it fits and abuts against the rear end 15 of the sleeve, as shown in Fig. 1.

To fill the reservoir B, the valve E is turned to withdraw the socket far enough to cause the vent-opening f' to clear the end of the barrel, whereby communication is afforded 20 through the vent of the interior of the barrel or reservoir with the air-space. Thereupon (the cap G being off) the sleeve F is drawn backward till its internal shoulder h' abuts against the shoulder f^4 , with the result of forcing the air contained in the space g through the vent f into the reservoir and driving out through the quill any remnant of ink that may be in the reservoir. Thus, as will be 25 seen, the fountain-pen is rendered in a sense self-cleaning. With the parts in the relative positions shown in Fig. 2, to which they are brought by the described operation, the reservoir is ready to be filled by restoring the barrel and the sleeve to their telescopically 30 folded or contracted positions. To accomplish the filling the device is immersed at the pen, or at the quill end if the pen is not in place, into the supply of ink, when the sleeve F is pushed forward upon the barrel until it meets the shoulder a , thereby sucking the air into the space g through the vent f' out of the reservoir and creating a sufficient vacuum in the latter to draw into it and fill it with ink from the supply. Thereupon 35 the valve E is closed by screwing the plug in to cover the vent f' and abut it against the rear end of the reservoir. As will thus be seen, the reservoir is equipped with a suction-filling attachment comprising in its broadest sense a contractible and expandable chamber surrounding and controllably communicating through a valve with the reservoir and operating by contracting it to evacuate the reservoir of its contents and by expanding it to suck ink into the reservoir. 40 With the reservoir thus filled the parts of the device are, as will be seen, in their most compact relative positions for use, from which it is only required to extend them preparatory to filling the reservoir. It will also be seen from the foregoing description that my improved construction reduces a fountain-pen equipped with a suction-filling attachment to a peculiarly few number of parts—namely, 45 the five parts comprising the barrel and pen-stock, the valve, the quill, the sleeve, and the cap—the construction enabling the barrel and pen-stock to be formed in one jointless piece. It will further be seen that the construction is comparatively simple, that the capacity of the reservoir is comparatively great, since no portion of its capacity when

filled is taken up by anything besides ink, and that the reservoir is proof against leaking, since it is adapted to be efficiently sealed 70 at its outer end by the valve and is also effectively sealed at the forward end in the common manner, so that no bearings are accessible to the ink in the reservoir.

To enable my invention to be readily understood, I have confined the description of the construction precisely to the details thereof illustrated in the drawings. However, I do not limit my invention to such details nor to the particular combinations shown and described, as they may be variously modified without departure from the spirit of my invention.

What I claim as new, and desire to secure by Letters Patent, is—

1. In a fountain-pen, the combination with a barrel forming the ink-reservoir, of a reservoir-sealing valve comprising a plug having a vented socket screwing upon the rear end of said barrel to close said end by abutting it 90 against the base of said socket, whereby the vent is covered and closed by the circumferential barrel-surface, said socket unscrewing on said rear end to withdraw said socket-base from contact with the barrel end and retract 95 the vent beyond said end, substantially as described.

2. In a fountain-pen, the combination with the ink-reservoir of a suction filling attachment thereon comprising a contractible and 100 expandable chamber surrounding and having valve-controlled communication with said reservoir, whereby contraction of said chamber evacuates the reservoir of its contents and expansion of the chamber sucks into the 105 reservoir ink from a supply thereof, substantially as described.

3. In a fountain-pen, the combination with the ink-reservoir, of a suction filling attachment thereon comprising a telescopic chamber surrounding and having valve-controlled communication with said reservoir, said chamber being contractible by retraction to evacuate the reservoir of its contents, and expandible by advancing it to suck into 115 the reservoir ink from a supply thereof, substantially as described.

4. In a fountain-pen, the combination with a barrel forming the ink-reservoir, of a sealing and filling valve on the rear end of the 120 reservoir, and a sleeve telescopically surrounding said barrel and forming about it a closed air-space controllably communicating with the reservoir through said valve.

5. In a fountain-pen, the combination with a barrel forming the ink-reservoir, of a reservoir sealing and filling valve comprising a plug having a vented socket screwed upon the rear end of the barrel, and a sleeve telescopically surrounding said barrel and forming about it a closed air-space controllably communicating with the reservoir through the vent in said socket.

6. A fountain-pen, comprising, in combi-

nation, a one-piece combined pen-stock and barrel forming the ink-reservoir, a quill in said stock for confining a pen and feeding thereto ink from the reservoir, a reservoir sealing and filling valve on the rear end of the barrel, and a sleeve telescopically surrounding said barrel and forming about it a closed air-space controllably communicating with the reservoir through said valve, to operate substantially as described.

7. A fountain-pen, comprising, in combination, a one-piece combined pen-stock and barrel forming the ink-reservoir, a quill in said stock for confining a pen and feeding thereto ink from the reservoir, an enlargement on the barrel presenting shoulders at its opposite ends, a valve composed of a plug

terminating at one end in a projection and at its opposite end in a vent-containing socket screwed upon the rear end of said barrel and 20 presenting a shoulder at its extremity, a sleeve telescopically surrounding said barrel and having an internal enlargement presenting a shoulder and forming between said shoulder and the circumference of said plug 25 a closed air-space about said barrel, and a pen-covering cap, the whole being constructed and arranged to operate, substantially as described.

CHARLES G. SOUTHMAYD.
